UNITED STATES PATENT OFFICE

CHARLES A. MUREAU, OF LOS ANGELES, CALIFORNIA

POWDER PUFF

Application filed May 21, 1930. Serial No. 454,273.

This invention relates to a powder puff and it is a general object of the invention to provide a simple, attractive powder puff adapted to hold a supply of face powder, or 5 the like.

An object of the invention is to provide a simple unitary article in the form of a powder puff which is adapted to hold a supply of a comminuted substance such as face powder, 10 or the like, and which embodies means whereby the powder may be readily applied or used.

Another object of the invention is to provide a powder puff of the character mentioned in which the powder held within the puff 15 cannot accidentally be lost or fall from the puff.

It is another object of the invention to provide a powder puff of the character mentioned that may be formed entirely of fabric 20 so that it is particularly convenient to handle and use.

A further object of the invention is to provide a powder puff of the character mentioned that is formed of but two simple parts 25 and is extremely inexpensive of manufacture.

Other objects and features of my invention will be best and more fully understood from the following detailed description of a typical manner of carrying out the invention, 30 throughout which description reference is had to the accompanying drawings, in which:

Fig. 1 is a side elevation of a bag or receptacle for carrying the puff. Fig. 2 is a side elevation of the carrier illustrating the flap 35 in the open position. Fig. 3 is a side elevation of the porous element of the puff. Fig. 4 is a view of the non-porous element or back of the puff illustrating it apart from the porous portion of the article. Fig. 5 is a view 40 of the non-porous back of the puff illustrating the manner of folding or bending it before it is secured to the front or porous portion of the puff. Fig. 6 is an enlarged view of the rear of the puff illustrating the flap in the 45 open position. Fig. 7 is a vertical detailed sectional view taken as indicated by line 7-7 on Fig. 6. Fig. 8 is a view of the rear or back of the puff illustrating the flap in the down or closed position.

The powder puff provided by this inven-

tion includes, generally, two main parts, one a porous element 10 permeable to face powder, or the like, which is adapted to be used for applying the powder, and a non-porous element 11 secured to the element 10 forming 55 a back for the puff and attached to the member 10 in a manner to provide a space or pocket 12 for carrying powder. The non-porous element 11 is provided with an integral flap 13 which is provided to form a closure for the filling opening 14 of the space 12.

The porous element 10 forms one side or the front of the puff and is adapted to be used for applying powder. The element 10 65 may be formed of any suitable material or fabric and may be of any desired shape. In the form of the invention illustrated the element 10 is shown as being in the form of a round disc. The element 10 is formed of a material that is readily penetrated by a finely divided or comminuted substance such as face powder, and it is preferred to form the element 10 of a material having a soft nap 70 on one side. The element 10 is arranged so 75 that its soft nap side is outward or on its outer side.

The non-porous element 11 forms the back of the puff and is secured to the element 10 in a manner to provide the space 12 for holding or carrying the face powder. The element 11 is impervious to powder, or the like. The element 11 may be formed of any suitable material, it being preferred to form the element 11 of a fabric that is more or less 80 flexible as well as impervious to powder. The outer side or back of the element 11 may be colored or suitably ornamented as desired. The element 11 includes a main or body portion 15 and the flap 13.

The body portion 15 of the element 11 is preferably of the same configuration as the element 10. In the form of the invention illustrated the body portion 15 is round or in the form of a disc. In accordance with the invention the body portion 15 of the element 11 is secured to the element 10 at its outer edge or periphery. The body portion 15 may be secured to the element 10 by suitable stitching 16 which acts to bind the edges 160

of the elements 10 and 11 as well as to secure them together. The stitching 16 extends around the edges of the elements 10 and 11 between the opposite sides or edges of the 5 flap 13 which projects from the edge of the main portion 15 of the element 11. The elements 10 and 11 are not secured together at the line of joinder of the flap 13 and the body portion 15 of the element 11. This provides 10 the filling opening 14 for the space or pocket 12.

The flap 13 is preferably integral with or formed of the same piece of material as the body portion 15 of the element 11. The flap 15 13 projects radially outward from the edge or periphery of the body portion 15 at the opening 14 as described above. The flap 13 as initially formed is substantially round or disc like in its general configuration. Fig. 20 4 of the drawings illustrates the element 11 as initially formed showing the configuration of the flap 13. A semi-circular cut 17 is formed in the inner portion 18 of the flap 13. The cut 17 is preferably formed concentric to the outer edge or periphery of the flap. The cut 17 preferably terminates at 25 diametrically opposite points as illustrated in Figs. 4 and 6 of the drawings. The element 11 is bent or folded at the line of joinder between the body portion 15 and the flap 13 so that the inner portion 18 of the flap is normally against the outer side or back of the body portion 15 and the flap 13 is bent or folded so that its outer portion 19 is folded 30 back upon the inner portion 18. The flap 13 is preferably bent or folded at the points of termination of the cut 17 so that the central portion of the flap 13 is not bent and remains flat to project outwardly from the flap at the 35 line along which the flap is folded or bent. This central projecting portion of the flap forms a tab 20 which normally rests against the body portion 15 of the element 11. The tab 20 formed in this manner provides an 40 opening 21 in the inner portion 18 of the flap. The opening 21 communicates with the filling opening 14 when the flap 13 is in the up or out position illustrated in Fig. 7 of the drawings. The opening 21 is of semi-circular configuration.

A radially projecting flange 22 is provided at the edge of the flap 13. The flange 22 is provided at the outer edge of the outer portion 19 of the flap. The outer edge of the 55 flange may be curved while the opposite side edges 40 of the flange may be inwardly divergent as clearly illustrated in Figs. 4 and 8 of the drawings. The outer curved edge of the flange 22 is secured to the edge portion 60 of the element 10 at the opening 14. The flange 22 may be secured to the element 10 by suitable stitching 23. In practice, the stitching 23 may be a continuation of the line of stitching 16. If desired, the feed or spacing 65 of the stitching 23 may be finer or closer than

that of the stitching 16. The stitching 23 is such that the flap 13 is normally held in the closed position against the body portion 15 of the element 11. In accordance with the invention the side edges 40 of the flanges 22 70 are stitched to the body 15 of the element 11. Cuts or notches 24 are made in the edge of the portion 15 at the points where the edges 40 of the flange are stitched to the portion 15. The notches 24 permit the flap to be 75 raised and operated to open the opening 14 without tearing the flange 22 or the body portion 15. The stitching 23 acts to maintain the flap 13 in its proper folded position against the body portion 15 of the element 10 where it forms a closure for the filling opening 14. When the flap 13 is raised to the position illustrated in Fig. 7 of the drawings and pressure is applied to the opposite peripheral edges of the flap to bulge the sides 80 of the flap outward, powder may be filled through the openings 21 and 14 into the space 12. When the flap is raised it tends to bend along the line of joinder of the flange 22 with the portion 15 shown by the broken line 41 in 85 Fig. 8.

In Figs. 1 and 2 of the drawings I have shown a bag or receptacle 30 for carrying the powder puff. The receptacle or carrier 30 is provided to contain the powder puff so that 90 it may be readily carried in a pocket or purse. The carrier 30 may be of any suitable formation. The carrier 30 is preferably formed of a non-porous material or fabric that is impervious to face powder. The carrier 30 100 may be formed of the same material as the back or element 11 of the puff. In the particular case illustrated the carrier 30 is shown as formed of a single piece of material having opposite parallel side edges 31. The piece of material forming the carrier 30 is folded back upon itself so that the side edges 31 may be stitched together by suitable stitching 32. A flap 33 may be provided at the open end of the carrier 30. The flap may be formed with a rounded outer end and the stitching 32 may extend continuously along the edges 31 and the edges of the flap 33. The carrier 30 is proportioned to carry the powder puff provided by the invention 110 and provides a means for readily carrying the puff.

It is believed that the utility and practicability of the puff provided by the present invention will be readily understood from the foregoing detailed description. It is to be noted that the entire article is formed of but two sections or pieces of fabrics. It is further to be noted that the puff is of extremely simple construction and inexpensive 120 of manufacture. The flap 13 and features associated therewith form an effective means for normally closing the filling opening 14 at the edge of the puff and also form a means for handling or using the puff. The stitch- 125

- ing 23 and the stitching securing the edges 40 to the body portion 15 act to secure the outer portion 19 of the flap in its proper position and also act to normally maintain the flap 13 in its closing position against the body portion 15 of the element 11. The side edges 40 of the flange 22 being secured to the body of element 11 positively hold the flap in the closed position until deliberately opened.
- 10 To fill powder into the puff, the flap is raised and pressure is applied to the opposite peripheral edges of the flap so that the portions 18 and 19 are bulged apart. This also widens the opening 14 so that powder may be readily filled into the space 12.

Having described only a typical preferred form of my invention, I do not wish to limit myself to the specific details set forth, but wish to reserve to myself any changes or variations that may appear to those skilled in the art or fall within the scope of the following claims.

Having described my invention, I claim:

1. A powder puff including, an element porous to powder, an element impervious to powder secured to the porous element, there being a space between the elements having a filling opening, and a closure means for the opening including, a flap integral with the
- 25 impervious element stitched to the porous element at the opening in a manner to be normally folded over the opening.

2. A powder puff including, an element porous to powder, an element impervious to powder secured to the first-mentioned element at its edge only to form a space between the elements, there being a portion of the edge of the porous element free of the impervious element forming an opening for the space, and closure means for the opening including a flap integral with the impervious element joining the impervious element at the opening, and means permanently attaching the opposite edge of the flap to the porous element 45 at the opening, so that the flap normally lies against one of the elements and closes the opening.

3. A powder puff including, an element porous to powder, an element impervious to powder secured to the first-mentioned element at its edge to form a space between the elements, there being a portion of the edge of the porous element free of the impervious element forming an opening for the space, and closure means for the opening including a flap joining the impervious element at the opening, and stitching securing the opposite edge of the flap to the porous element at the opening in a manner so that it normally folds 60 over the opening.

4. A powder puff including, an element porous to powder, an element impervious to powder secured to the first-mentioned element at its edge only to form a space between the

elements, there being a portion of the edge of the porous element free of the impervious element forming an opening for the space, and closure means for the opening including a flap integral with the impervious element joining the impervious element at the opening, and stitching securing the opposite edge of the flap to the porous element at the opening so that it normally folds over the opening and closes it.

5. A powder puff including, an element porous to powder, an element impervious to powder secured to the first-mentioned element at its edge only to form a space between the elements, there being a portion of the edge of the porous element free of the impervious element forming an opening for the space, and closure means for the opening including a flap integral with the impervious element joining the impervious element at the opening and having a flange at its opposite edge, and stitching permanently securing the flange to the porous element at the opening so that the flap normally folds over the opening and closes it.

6. A powder puff including, an element porous to powder, an element impervious to powder secured to the first-mentioned element at its edge only to form a space between the elements, there being a portion of the edge of the porous element free of the impervious element forming an opening for the space, and closure means for the opening including a flap integral with the impervious element joining the impervious element at the opening and a radial flange at the opposite edge of the flap, and stitching securing the outer edges secured to the porous element at the opening and the side edges of the flange to the impervious element, so that the flap is normally folded over the opening against the impervious element.

7. A powder puff consisting solely of a porous element and an impervious element, the edges of the elements being secured together to provide a space between them for holding a comminuted substance, there being an edge portion of the porous element free of the impervious element forming a filling opening for the space, the impervious element having a flap normally folded back upon its outer side at a line adjacent said filling opening, the flap being folded back upon itself to have an edge portion at the filling opening, the said edge portion being permanently secured to the porous element at the filling opening so that the flap is normally retained in the position where it lies against the impervious element and closes the filling opening.

8. A powder puff including a porous element, an impervious element, the elements being secured together at their edges to provide a space between them for holding a comminuted substance, the porous element having an edge portion free of the impervious

element forming a filling opening for the space, and a flap joining the impervious element at the filling opening and bent along a line adjacent the filling opening to lie against the outer side of the impervious element, the flap being folded back upon itself to have an edge at the filling opening, and means permanently attaching the said edge of the flap to the porous element so that the flap normally remains folded back upon itself and lies against the outer side of the impervious element to close the filling opening.

9. A powder puff including a porous element, an impervious element, the elements being secured together at their edges to provide a space between them for holding a comminuted substance, the porous element having an edge portion free of the impervious element forming a filling opening for the space, and a flap joining the impervious element at the filling opening and bent along a line adjacent the filling opening to lie against the outer side of the impervious element, the flap being folded back upon itself to have an edge at the filling opening, and means permanently attaching the said edge of the flap to the porous element so that the flap normally remains folded back upon itself and lies against the outer side of the impervious element to close the filling opening, the flap having an opening in its under side communicating with the filling opening when the flap is raised away from the outer side of the impervious element.

35 10. A powder puff including a porous element, an impervious element, the elements being secured together at their edges to provide a space between them for holding a comminuted substance, the porous element having an edge portion free of the impervious element forming a filling opening for the space, and a flap joining the impervious element at the filling opening and bent along a line adjacent the filling opening to lie against the outer side of the impervious element, the flap being folded back upon itself to have an edge at the filling opening, and means permanently attaching the said edge of the flap to the porous element so that the flap normally remains folded back upon itself and lies against the outer side of the impervious element to close the filling opening, the flap having a cut in its under side to form an opening to communicate with the filling opening when the flap is raised away from the outer side of the impervious element, a part of the flap bounded by said cut projecting from the edge of the flap at the line along which the flap is bent upon itself to form a lifting tab.

60 11. A powder puff including a porous element, an impervious element, the elements being secured together at their edges to provide a space between them for holding a comminuted substance, the porous element having an edge portion free of the impervious

element forming a filling opening for the space, and a flap joining the impervious element at the filling opening and bent along a line adjacent the filling opening to lie against the outer side of the impervious element, the flap being folded back upon itself to have an edge at the filling opening, and means permanently attaching the said edge of the flap to the porous element so that the flap normally remains folded back upon itself and lies against the outer side of the impervious element to close the filling opening, the said means including stitching connecting the said edge of the flap to the porous element.

In witness that I claim the foregoing I have hereunto subscribed my name this 6th day of March, 1930.
